UNITED STATES PATENT OFFICE.

JOHN C. HARING AND CHARLES H. COURT, OF JERSEY CITY, NEW JERSEY.

STYLOGRAPHIC FOUNTAIN-PEN.

SPECIFICATION forming part of Letters Patent No. 298,084, dated May 6, 1884.

Application filed October 5, 1883. (No model.)

To all whom it may concern:

Be it known that we, JOHN C. HARING and CHARLES H. COURT, residents of Jersey City, Hudson county, and State of New Jersey, have 5 invented certain new and useful Improvements in Stylographic Fountain-Pens; and we do hereby declare that the following is a clear and full description thereof, reference being had to the accompanying drawings, which form a 10 part of this specification.

This invention relates to stylographic or fountain pens; and it consists in certain details of construction and combinations of parts, as hereinafter pointed out and claimed.

15 The object of the invention is to simplify the construction and improve the operation of stylographic fountain-pens.

Figure 1 is a central longitudinal section of an improved stylographic fountain-pen. Fig. 2 is a broken sectional view of the same. Fig. 3 is a central longitudinal section showing a modification of the spring for vibrating the needle-point. Fig. 4 is a broken sectional view of a stylographic fountain-pen, showing 20 the spring and needle-holder within the end of the air-tube. Fig. 5 is a central longitudinal sectional view of a stylographic fountain-pen, showing the air-tube and spring in one piece. Fig. 6 is a broken sectional view showing a modification of the needle-holder and spring. Fig. 7 is a broken sectional view showing a modification of the manner of supporting the spring needle-holder. Fig. 8 is a 25 cross-section of a stylographic fountain-pen cutting through on the line *ee*, shown in Fig. 7.

Like letters of reference indicate corresponding parts in all of the figures.

The stylographic fountain-pen shown in the several figures consists of the case A, air-tube 40 C, and writing-point B. The extension-plug or spring-guide *g* is connected with the air-tube C. The lower end of this plug guides and keeps the spring-tube *h* in position.

The tube *h* can be made of any suitable elastic or semi-elastic material not affected by the corrosive qualities of the ink, and which will admit of a spring to be formed thereof by cutting away, in any suitable manner, a suitable portion of the material forming said tube.

50 The lower end of this tube is provided with a plug carrying the needle-point *f*; but it may

be dispensed with by substituting therefor a tube with a bottom of suitable thickness to receive and hold the needle firmly therein. The spring can also be formed by cutting a spiral 55 channel around a solid cylindrical piece. This channel must be cut deep enough to pass the center of the cylinder, thereby leaving a tubular spring with solid ends.

The needle-holder shown in Fig. 3 consists 60 of a plug, *b*, inserted in tube *h*. The tube is connected to the extension-piece *g*, while between this extension and needle-holder *b* a suitable spring is placed for the purpose of vibrating the needle.

The air-tube C shown in Fig. 4 is provided with a plug, *a*, and needle-holder *b*, which is 65 vibrated by spring *c*.

The air-tube C shown in Fig. 5 is provided on its lower end with a suitable spring, formed 70 by cutting therefrom a portion of the tube itself. The lower end of the spring is provided with a needle-holder, *b*, while the upper end of the air-tube is provided with a screw, *D*, for the purpose of extending the needle after 75 the point wears away.

A modification of the air-tube C and spring *c* is shown in Fig. 6, wherein the plug *a* is forced into the tube in a suitable fixed position, after which a rubber or other suitable 80 spring, *c*, can be inserted and kept in place by needle-holder *b*, the needle-holder being kept in position by friction, or by a pin, *i*, working in slot *k*.

The needle-point can be advanced when 85 worn away by removing the cap F and turning the air-tube C.

A modification of an adjustable spring-needle and holder is shown in Fig. 7, a cross-section of which is shown in Fig. 8.

90 What we claim, and desire to secure by Letters Patent, is—

1. In a stylographic fountain-pen, the combination of the case, the air-tube formed as described, to constitute a spring at its lower 95 end, and the needle arranged within the case so as to have a bearing against said spring, whereby a vibratory or reciprocating movement is permitted to the needle, substantially as described.

2. In a stylographic fountain-pen, the case, the air-tube inclosed thereby, said tube being 100

cut away as described, to form a spring, and being provided with a plug (as *g*) near its lower end, and the needle arranged in the casing to bear against said spring, all the parts in combination substantially as and for the purpose set forth.

3. In a stylographic fountain-pen, a case provided with a part internally screw-threaded, an air-tube having an external screw-thread to engage therewith, said air-tube being cut

away in part at its lower end to form a spring, and a needle arranged, substantially as described, to bear against said spring, all in combination substantially as and for the purpose set forth.

JOHN C. HARING.

CHARLES H. COURT.
